WRITING INSTRUMENT

Arthur F. O'Connor, Chicago, Ill.

Application June 28, 1946, Serial No. 680,129

5 Claims. (Cl. 120—42.4)

1

The invention relates to fountain pens of the type using a writing material having a pasty consistency and more particularly to pens of this type employing a rotatable writing ball at the forward tip of the pen.

An object of the invention is to provide new and novel means for selectively urging the pasty writing material forward in the barrel of the pen as the writing material adjacent the writing ball becomes used up.

Another object is the provision of improved means for preventing leakage of the writing material through the assembled parts at the rear end of the pen barrel.

A further object is to provide improved means for advancing the mass of writing material in the pen barrel by pushing a button at the rear end of the pen barrel each time it is desired to urge the writing material forward in the barrel.

Another object is to provide simple and positive means for selectively advancing the writing material pleasing in appearance and having appeal to pen users.

A further object is the provision of improved means for moving the writing material forward in the pen barrel adapted to move the entire mass of writing material forward and wiping the walls of the bore of the barrel whereby none of the writing material is left adhering to said walls rearwardly of the mass of writing material, thereby increasing the time between pen fillings.

Another object is the provision of improved gasket means adapted to prevent leakage therethrough as it is moved forwardly in the pen barrel.

A further object is to provide a piston adapted to be moved a predetermined distance toward the gasket and writing material with provision intermediate the piston and the forward portion of the gasket of resilient means exerting a resilient pressure against the rear end of the mass of writing material.

Other objects, advantages and capabilities of the invention will be apparent from the following description when read in conjunction with the accompanying drawings, in which:

Figure 1 is an axial section through a pen embodying the invention.

Fig. 2 is an elevational view of the pen of Fig. 1.

Fig. 3 is an enlarged fragmentary axial section taken along line 3—3 of Fig. 1.

Fig. 4 is a sectional view taken along line 4—4 of Fig. 3.

It is to be understood that the present invention relates to improved means for feeding the pasty writing material to the writing ball of the pen.

Throughout this specification, the word "forward" is intended to mean toward the writing

2

ball and the word "rear" is intended to mean the opposite direction.

In the drawing, the preferred form of my invention comprises a main body portion or barrel 10, a tip member 12 removably secured to the forward end of the barrel 10, a nipple member 14 removably secured to the rear end of the barrel, a cap member 16 removably secured to the rear end of the nipple member, a spring 18 intermediate the assembled nipple member and cap member, a piston 20 and an associated gasket 22 adapted for longitudinal movement within the bore of the barrel and a plunger rod 24 adapted to selectively move the associated piston and gasket forwardly in the bore of the barrel, the spring 18 being adapted to normally urge the plunger rod in a direction toward the rear end of the barrel. The space 26 forwardly of the gasket 22 may be filled with a pasty writing material; Fig. 1 illustrating the relative position of the several parts of the pen when it is filled with writing material.

The nipple member 14 may comprise a sleeve provided with a central bore 28 adjacent its rear end portion, a transverse wall 30 defining the forward end of the bore 28. The opposed ends of the nipple member may be externally threaded, the opposed threaded ends being separated by an outwardly-projecting lateral ring portion 32 larger in diameter than the said threaded ends, adapted to serve as a shoulder member to abut the rear end of the barrel and the forward end of the cap member of the assembled pen.

The cap member 16 may comprise an end wall 34 formed with a central aperture therethrough and circular depending side walls 36 internally threaded to register with the rear threaded end of the nipple member 14. The bore 28 of the nipple member 14 and the bore of the assembled cap member 16 may be of uniform diameter adapted to form a cavity for housing the spring 18.

The piston 20 may comprise a cylindrical member 21 slightly smaller in diameter than the diameter of the bore of the barrel 10 adapted for sliding movement in the bore of the barrel. The piston may have a central aperture 38 therethrough and may be provided with a pair of resilient members 40 rigidly secured to the piston and extending rearwardly on opposed sides of the aperture 38. The opposed resilient members 40 may be normally urged at their free ends toward each other into engagement with the opposed sides of the plunger rod 24. The piston may be made of a hard or semi-hard material, such as vulcanized rubber, plastics and the like. The secured ends of the members 40 may be formed with angular portions 41 adapted to interlock the members 40 with the piston member, the portions 41 being particularly adaptable for this

purpose where the piston is moulded of plastic material.

The gasket 22 may be made of a yieldable material such as rubber, felt, leather and the like and may comprise a cup-shaped member having a wall 42 disposed transversely of the bore of the barrel 10 and in flatwise abutting relation with the forward surface of the piston 20. The peripheral portion of the wall 42 may be formed with a depending forwardly extending wall 44 adapted to closely register with the bore in the barrel. The inner surface of the wall 44 may taper inwardly and rearwardly from a relatively thin edge to the wall 42. The wall 42 may be formed with a sleeve 46 extending forwardly therefrom and defining a central aperture 48 coaxial with the bore of the barrel 10. The outer wall of the sleeve 46 may taper outwardly and rearwardly from a relatively thin edge to the wall 42. The aperture 48 may be of uniform diameter throughout its major forward length and may be formed with an enlarged portion 50 adjacent its rear end. The gasket may be secured to the adjacent surface of the piston 20 as by bonding the gasket to the piston.

The plunger rod 24 may comprise an elongated round rod formed at its rear end with an enlarged "push-button" member 52. A laterally disposed washer-like member 54 of larger diameter than the diameter of the member 52 may be formed on the rod adjacent the connection of the rod with the member 52. The forward and rear end portions of the rod may be plain for a predetermined length and the intermediate portion of the rod may be provided with a series of abutments 56 cut or otherwise formed therein. The forward end of each abutment 56 may be equal in diameter to the diameter of the rod and each abutment may taper rearwardly and inwardly from its forward end to the next adjacent abutment.

So far in the specification, the several component parts of the invention have been described separately. I will now describe the assembled parts and point out the cooperative relation of one part with another.

The associated piston 20 and gasket 22 may be disposed within the barrel 10 in the relative position indicated in Fig. 1 when the space 26 of the barrel is filled with writing material. The plunger rod 24 may be centrally and longitudinally disposed within the bore of the barrel 10 with the abutment portion of the rod extending through the aligned apertures 38 and 48 of the piston and gasket, respectively. The rear plain end portion of the plunger rod may extend through a central aperture 31 of the wall 30 of the nipple member 14 with the member 54 of the rod normally held in abutting relation with the inner surface of the end wall 34 of the cap member by the spring 18; the spring 18 being normally under compression in its assembled position, with its rear end portion abutting the member 54 and its forward end portion abutting the wall 30. The "push-button" member 52 may extend through the central aperture in the wall 34 of the cap member and may extend rearwardly of the wall 34 a predetermined distance substantially equal to the desired forward stroke of the plunger rod required to move the piston forward a notch at a time. Viewing Fig. 1, the opposed free ends of the resilient members 40 may be in abutting relation with the abutment nearest the rear end of the plunger rod whereby, upon the forward movement of the plunger rod, the piston 20 will be moved forward in the barrel 10 a distance equal

to the stroke of the plunger rod, this distance being substantially equal to the distance between adjacent abutments 56 of the plunger rod.

Upon each forward stroke of the plunger rod, the piston 20 and associated resilient members 40 will be advanced in the barrel a distance equal to the length of an abutment 56 and the plunger rod will return to its normal position by means of the spring 18. During the return movement of the plunger rod, the opposed free ends of the resilient members 40 will move into interlocking engagement with the next forward abutment of the plunger rod, adapted to maintain the piston in its last advanced position and place the plunger rod in position where, upon the next forward stroke thereof, the piston will be advanced another notch. It will be understood that the members 40 require only enough "spring" to urge them at all times into engagement with the plunger rod and it will be seen from the drawing that the friction between the members 40 and the tapered side walls of the abutments 56 will be so negligible that there will be no tendency for the spring-urged return of the plunger rod to pull the piston back with it. While I have shown the resilient members 40 as being substantially flat in cross-section I contemplate the use of members 40 concavo-convex in cross-section in order to provide longitudinal rigidity of the members 40.

It will be understood that, upon forward advancement of the piston and associated gasket, the mass of pasty writing material will be moved forward bodily and a slight pressure may be built up through the resiliency in the gasket at the rear of the mass of writing material if desired to insure the proper feeding of the writing material to the writing ball. It will be further understood that a full stroke of the plunger rod may not be necessary; the user of the pen being able to determine by experience whether a full stroke is desirable or whether less than a full stroke may be sufficient to feed the supply of writing material to the writing ball.

When the push-button member 52 is pushed inwardly the gasket 22 will be urged forwardly in the pen barrel, the wall 44 of the gasket being held in substantial sealing relation with the walls of the pen barrel by the compressed writing material. As the gasket moves forwardly in the pen barrel the last mentioned sealing relation will wipe the walls of the pen barrel, eliminate the possibility of any of the writing material adhering to the walls of the pen barrel rearwardly of the advancing gasket (eliminating leakage of the writing material at the cap member) and insure the use of the maximum amount of the supply of writing material; the latter increasing the length of periods between pen fillings. The sleeve 46 of the gasket 22, being resilient, will be pressed into sealing engagement with the contour of the abutment portion of the plunger rod by the action of the compressed writing material against the sleeve 46, thereby preventing leakage of the writing material from the forward reservoir 26 through the aligned apertures 38 and 48 of the piston and gasket, respectively. The rear end portion of the aperture 38 may be formed with an enlarged portion 60 similar to the enlarged portion 50 of the aperture 48; both enlarged portions being adapted to permit the abutments 56 of the plunger rod to enter the apertures 38 and 48 without interference. An aperture 58 may be formed in the forward end of the plunger rod for insertion therethrough of a pin or other suitable

detent member adapted for the purpose of engaging the gasket for retraction thereof when the supply of writing material has been used up and the plunger rod is moved rearwardly to its initial rearward position.

It will be understood that the spring 18 may be replaced with other suitable resilient means, if desired. I contemplate the use of a spring 18 or equivalent having resistance to compression sufficient to prevent the accidental forward movement of the plunger rod and I further contemplate the use of a supplemental cap removably secured to the cap member 16 adapted to prevent pushing the plunger rod forward while the supplemental cap is in secured position.

I do not contemplate an air-tight fit between the plunger rod and the members 14 and 16.

I contemplate the use of a combined piston and gasket, such as a piston having the equivalent of resilient piston rings at its periphery although I prefer the structure shown in the drawings in order to provide some resiliency or "give" intermediate the writing material and the piston. The wall 42 of the gasket may be considerably thicker than shown in the drawings and may comprise a relatively soft, yieldable material whereby, when the plunger rod is pushed forward, the resiliency in the wall 42 may exert a light pressure against the mass of writing material not sufficient to force it out around the writing ball. Any suitable resilient means may be used intermediate the writing material and the piston. I propose to charge the pen barrel through the forward end thereof to avoid possible entrapment of air between the gasket and the writing material such as might occur if the barrel were charged from the rear end thereof.

It is an object of the present invention to prevent leakage of the writing material adjacent the rear end of the pen barrel and to this end I prefer a gasket as shown in the drawings, having rearwardly tapering flexible walls 44 and a rearwardly tapering flexible sleeve 46. When the gasket is urged forwardly in the pen barrel, by the piston, the wall 44 will be urged into sealing engagement with the inner bore of the pen barrel due to a slight pressure in the mass of writing material against the wall 44. The resilient sleeve 46 may be similarly pressed into sealing engagement with the contour of the abutment portion of the plunger rod by this same pressure, this sealing engagement being relieved as the pressure in the mass of writing material is reduced, as it will be when the next forward movement of the plunger rod is indicated as being desirable.

While a preferred embodiment of the invention has been shown and described herein, it will be understood that this is merely illustrative and is not to be taken as a definition of the scope of the invention, reference being had for this purpose to the annexed claims.

I claim:

1. A fountain pen including a hollow barrel, a piston slidable in the barrel formed with an axial aperture, an elongated plunger rod extending slidably through said aperture, said rod formed with a series of rearwardly tapered ratchet teeth, an elongated leaf spring affixed to and having its major portion disposed lengthwise of the barrel rearwardly of the piston, the rear end of said spring being adapted through tension therein to normally wipingly engage said teeth when the plunger rod is moved in one direction and adapt-

ed to engage said teeth interlockingly when the plunger rod is moved in the opposite direction whereby said plunger rod may be moved axially in said one direction without moving the piston and may be moved in said opposite direction to bodily move said piston, respectively.

2. The structure of claim 1 wherein a resilient gasket formed with an axial aperture is disposed forwardly of the piston, said gasket having a forwardly extending peripheral flange adapted to closely register with and wipingly engage the interior wall of the barrel, the inner wall of said flange tapering rearwardly and inwardly from a thin forward circular edge.

3. The structure of claim 1 wherein a resilient gasket is disposed forwardly of the piston formed with a forwardly extending central extension having an axial aperture therethrough in coaxial alignment with the plunger rod, the inner wall of said aperture being parallel with said rod and the outer wall thereof being tapered rearwardly and outwardly from a thin forward circular edge, said edge being adapted to wipingly engage the periphery of said rod when the latter is moved axially through said gasket.

4. A fountain pen including a hollow barrel, a piston formed with an axial aperture slidable in the barrel, an elongated plunger rod extending slidably through said aperture, said rod formed with a series of peripheral rearwardly tapered ratchet teeth, a pair of leaf springs secured to and having their major portions disposed lengthwise of the barrel on opposed sides of the plunger rod rearwardly of the piston, the rear ends of said springs being adapted through tension therein to wipingly engage said teeth when said rod is moved axially in one direction and adapted to interlockingly engage said teeth when the rod is moved in the opposite direction.

5. The structure of claim 4 wherein the rear ends of the springs are adapted to spread away from each other laterally of the barrel as the plunger rod is moved axially in one direction and adapted through tension in the springs to snap into interlocked relation with teeth as said rod is moved in said one direction a distance equal to the spacing between the teeth, whereby, upon moving said rod in the opposite direction, the piston will be moved bodily with the rod a distance equal to the stroke of the rod without lost motion between the rod and the piston.
